UNITED STATES PATENT OFFICE.

CHARLES S. CARD, OF DENVER, COLORADO.

COMBINED DRAWBAR AND AXLE-SUPPORTING APPARATUS FOR CAR TRUCKS.

1,419,716.

Specification of Letters Patent. Patented June 13, 1922.

Application filed March 4, 1922. Serial No. 541,108.

To all whom it may concern:

Be it known that I, CHARLES S. CARD, a citizen of the United States of America, residing at the city and county of Denver 5 and State of Colorado, have invented a new and useful Combined Drawbar and Axle-Supporting Apparatus for Car Trucks, of which the following is a specification.

My invention relates to a combined drawbar and axle supporting apparatus for car trucks.

And the objects of my invention are:

First. To provide ore, coal or other material conveying cars with combined truck 15 axle supporting journal boxes and draw-bar mechanisms that are supported and operatively arranged and are fully contained in one integral casting, and that can be quickly secured to the bottoms of the cars. 20 Second. To provide two independent, resilient yielding draw-bar mechanisms for the opposite ends of ore and other material carrying car trucks, that operate entirely independently of each other, but that 25 will operate at the same time or at different times, as when a single car is moved or a train of cars is moved.

Third. To provide a draw-bar apparatus that yields resiliently enough when starting 30 a car, when motive pulling power is attached to one end of it, to completely break the solid jerking of it, and that will start and move it with a gradual drawing movement, but which will, when the car is started, 35 draw it by a pull against a solid metal portion of its axle and draw-bar supporting housings, and which will at the same time, if another car is attached to the opposite end draw-bar mechanism of the car to which 40 the motive power has been attached, start that car with a resiliently yielding pull that also ends in a pull against the solid metal 45 of the draw-bar's housing.

I attain these objects by the mechanism 50 illustrated in the accompanying drawings, in which:

Figure 1 is a side elevation showing two coupled ore cars, constructed in accordance with my invention, one of the car trucks 55 being shown in longitudinal section, the other in side elevation.

Fig. 2 is a vertical transverse sectional view through one of the trucks, on the line 2-2 of Figure 1, the draw bar, and spring 60 surrounding the same being omitted.

Fig. 3 is a vertical sectional view through

one of the car wheels, showing the manner of securing the same upon the axle.

Fig. 4 is a plan view of one of the improved draw bar and axle supporting members.

Fig. 5 is a side view of the same, and Figure 6 is a transverse sectional view on the line 6-6 of Fig. 4.

Similar letters of reference refer to similar parts throughout the several views.

Two independently constructed but combined draw-bar and axle supporting mechanisms are placed under the truck portion 1 of each car body 2, one under each end 70 portion of each truck. They are both alike in construction, but their car pulling ends face in opposite directions, and as their constructive details are alike, the following description of one will apply to the other. 75

Referring to the drawings:

The numeral 1 designates the truck, the sides 3 of which are made of channel bars. The numeral 4 designates a casting, which I term the combined axle and draw-bar 80 mechanism supporting member of the truck 1. The casting 4 is secured by bolts 5 to the lower inside foot member 6 of the side bars 3.

The casting 4 is a one piece integrally 85 moulded casting, and it is made long enough to extend across the entire width of the under side of the truck and far enough beyond it to form journal boxes 7 at its ends. An axle 8 extends rotatably through 90 and beyond these journal boxes 7, and beyond them far enough to receive the car and truck wheels 9, which are mounted on the ends of the axles and are secured there by spring cotter pins 10, inserted in holes in the 95 outside hubs 11 of the truck wheels 9 and are passed through apertures in the end portions of the axle 8, the holes being closed by screw openings 12. The ends of the journal boxes 7 are made in the form of 100 sleeves 13 which are formed to extend over the hubs 11 of the car wheels, and they are also made enough larger than these hubs to form a packing box for a flax or other packing ring or band 13^A which is placed 105 in the sleeves around the hubs of the wheels, and retains the lubricant in the journal boxes 7. Washers 7^A are placed against the end walls of the boxes 7, which receive the wear of the inner ends of the wheel hubs 110 and a renewable hard steel lining sleeve 7^B is inserted in the wheel hub between which

sleeve and the axle are placed an endless series of solid steel rollers 7^c which are shorter than the length of the boxes, the bores of the boxes, beyond the outer ends 5 of the rollers, being enlarged to form grease chambers 7^b, a washer 7^e being held against the inner end wall of the grease chamber, by the cotter pin 10, which washer serves to hold the said rollers in place.

10 The journal boxes extend from the opposite ends of the casting 4 to within a short distance of the center of the length of the axle, and the casting is formed with a flat plate central portion 15 that stands above 15 and free from the axle, which arrangement brings all of the weight of the truck and the car on the axle in the journal boxes of the casting which are located under the opposite side edge portions of the underside 20 of the frame 3 of the truck 1.

A square-shaped open-topped box member 15^a, is formed in the center of the casting lengthwise of the truck, that has closed sides 16, and ends 17 and 17^a, and it is of a height 25 above the plate portion of the casting, and is also of a width to form a box shaped housing recess 18 for a coiled spring 19, and ribs 20 extend from the top edges and the sides of this box portion at an angle 30 down to the opposite edges of the flat portion of the casting.

The spring 19 is made to fit snugly in between the opposite end 17 and a collar 22 of the recess 18, and a draw-bar 23 is extended slidably and reciprocally through an aperture formed in the end 17 of the spring's housing box and also through a sleeve 24 that is mounted in the housing box of the spring, and beyond their opposite ends a 40 short distance, and the draw-bar extends loosely through the coils of the spring and supports the spring free from contact with the sides or bottom of the box, and the spring is free to move on the draw-bar independently of the reciprocal movement of the draw-bar when it compresses it or when the spring expands after being released by the draw-bar by compression, as will be 45 fully explained hereinafter.

50 The collar 22 is secured to the inner end of the sleeve 24, which is mounted loosely on the draw-bar and is also mounted slidably in the end 17^a of the spring's housing box, and this sleeve extends a short distance beyond the end 17^a of the box, and an abutment collar 25 is secured on its end.

The length of this sleeve between the inside of the abutment 25 and the end 17^a of the box is made of such a relative length to 60 the length of the spring and the combined distances between the coils of the spring that the abutment collar 25 will move and bear against the end 17^a of the box before the spring is fully compressed, so that its coils 65 would not come in bearing contact with each

other, or even in such close position to each other as would tend to crystallize and thus cause the spring to break from the repeated concussions it would receive if the collar and the draw-bar drew its coils tightly against 70 each other every time a car was started.

The inner terminal end portion 26 of the draw-bar is provided with a tapered key 27 that extends through the draw-bar and is secured to it by a split pin 28, and the key 75 is made long enough so that its ends extend across and bear against the collar. The opposite end of the draw-bar projects forward from the end 17 of the spring's housing box, and an eye disc 31 is formed at its 80 end, to which chain links 32 are connected.

I have preferably described the combined draw-bar and axle supporting apparatus of the front end 30 of the truck as illustrated in side elevation in Figure 1 of the drawings, but the other axle and its draw-bar mechanism are secured further back from the rear end 33 of the truck than the one at the end 30 of the truck, and its draw-bar 34 has to be made long enough to extend beyond the rear end of the truck in order to be readily connected to another car, and the end of the eyed and linked end of this draw-bar is provided with a hook 35, that will hook into the links like the chain links 95 32, on the front end of another car equipped with a duplicate set of rods, combined draw-bar and axle supporting apparatus.

The operation of my combined draw-bar and axle supporting apparatus for ore and 100 other material conveying cars is as follows:

Motive power, which may be of any suitable kind, such as animal, but which would probably be an electrically operated locomotive if long trains of loaded cars are to be hauled, is connected to the end links of the draw-bar 23 at the front end of the car 2 and its truck 1, and when the locomotive is started to start the train of cars which have been previously coupled together, the draw-bar 23 is pulled forward, its key 27 engages the collar 24 and pushes it and its sleeve and the collar 24 forward, which causes the collar 24, which is against the adjacent end of the spring, to compress the spring, which takes the whole strain of the pulling power of the motor, and this spring is made of a resilient tension that enables it to be compressed enough by the pull of the 110 motor to start the loaded car rolling on the track and to move it; therefore, the coils of the spring are compressed enough to almost but not quite bear against each other, and the collar 24 has moved up against the end 115 17^a of the spring's housing box when the draw-bar pulls the loaded car by means of the collar bearing against the spring's housing box, and the spring is relieved from further compression, and its coils will not be 120 125 130

compressed close enough to each other to cause the spring to crystallize and break.

The same resiliently yielding action takes place when the hook of the rear draw-bar 5 is connected to the front end of another car, then the long draw-bar compresses its spring 30^A in exactly the same way as the draw-bar 23 does the spring 19, until the abutment collar 25 at its end engages the end 10 17^A of the housing box of this draw-bar mechanism.

The holes X in the ends 17 of the boxes 15^A are square, and the portions of the draw-bars 23 and 34 which normally rest in these 15 holes, are also square in cross section, and the draw-bars are thus prevented from turning axially in the boxes 15^A, whereby the hooks 35 of the draw-bars 34 are prevented from becoming disconnected from the link 20 32 of the draw-bar 23.

I have thus provided duplicate sets of resiliently starting draw-box mechanism for the track member of each ore, coal or other material conveying car, which are placed at 25 its opposite end portions which, while wholly independent of each other, cooperatively assist in cushioning the starting movement of each car and of all the cars in a train of cars; that is, the resiliently yielding 30 draw-bars of all of the cars in a train of cars mutually coact to cushion the starting, slowing up and stop movement of each one and at the same time of all the cars in a train of cars. Consequently my invention 35 contemplates broadly the application of my non-breakable cushioning spring, and my combined draw-bar and axle supporting integral casting so arranged that all of the cars in a train of cars assist in cushioning 40 the starting movement of each other. And my invention also protects the springs from breakage by preventing the sudden and violent jamming of their coils together, and at the same time I have provided a one- 45 piece supporting casting member for the axles and for all of the elements of the two draw-bar mechanisms of each car's track; and while I have illustrated and described the preferred construction of my invention, 50 I do not wish to be limited to the detail construction and arrangement of the parts thereof, as changes may be made in it without departing from the spirit of my invention.

Having described my invention, what I claim as new and desire to secure by Letters Patent, is:

1. A draw-bar and axle-supporting mechanism operatively mounted in duplicate sets 60 on the opposite ends of cars, each set being independent of the other, and each mounted in one integral one-piece casting.

2. A draw-bar and axle-supporting mechanism operatively mounted in duplicate sets 65 on the opposite ends of cars, each set being

independent of the other, each of said draw mechanisms comprising a railway track wheel supporting axle, journal and lubricating packing boxes on said casting, said packing boxes being arranged to surround the 70 inner hubs of said track wheels.

3. A draw-bar and axle-supporting mechanism operatively mounted in duplicate sets on the opposite ends of cars, each set being independent of the other, and each 75 mounted in one integral one-piece casting, said casting being provided with a reciprocating draw-bar, a spring mounted on said draw-bar, and abutments at the opposite ends of said spring, one of which is arranged to compress said spring, and means connected with said draw-bar for limiting the compressive movement of said spring, and for bringing said draw-bar into pulling engagement with said casting at one end, 80 and car or motive power connecting means on the opposite outer ends of said draw-bars.

4. The combination in trucks of cars, of a one piece casting provided with a packing 90 box containing journal boxes and a compressive spring housing box, a compressive spring mounted in said housing box, and a draw-bar with a sliding sleeve member for compressing said spring, and means for connecting one car to another. 95

5. The combination in trucks of cars, of a one piece casting provided with a packing box containing journal boxes and a compressive spring housing box, a compressive 100 spring mounted in said housing box, and a draw-bar with a sliding sleeve member for compressing said spring, said sleeve member of said draw-bar being arranged to compress said spring when pulled to start 105 the car, and to engage said casting after said car has been started and before the coils of said spring have been compressed against each other.

6. The combination of a draw-bar apparatus for cars, comprising a one-piece casting at each end portion of said car, arranged to support the axle of the car, and a resiliently cushioning draw-bar mechanism mounted on each axle supporting casting arranged to 115 start the cars by the resilient means, but to pull it by a direct pull on said casting. 110

7. The combination of combined and duplicate sets of axle supporting and resiliently yielding draw-bar apparatus operatively 120 mounted in a one piece, integrally moulded casting, and secured to the opposite ends of cars.

8. The combination of combined and duplicate sets of axle supporting and resiliently yielding draw-bar apparatus operatively 125 mounted in a one piece, integrally moulded casting, and secured to the opposite ends of cars, said axle supporting casting being provided with journal boxes fitting the axles of 130

said trucks, and having packing box members at their outer ends.

9. The combination of combined and duplicate sets of axle supporting and resiliently yielding draw-bar apparatus operatively mounted in a one piece, integrally moulded casting, and secured to the opposite ends of cars, said axle supporting casting being provided with journal boxes fitting the axles of 10 said trucks, and having packing box members at their outer ends, said draw-bar apparatus comprising a housing box portion, a compressive spring in said housing box, a draw-bar extending through said housing 15 box and spring, and means mounted on said draw-bar for compressing said spring a predetermined part of its coil closing movement, and means whereby said draw-bar engages said casting's housing box when said 20 spring is at the end of its adjusted compressive movement.

10. The combination of combined and duplicate sets of axle supporting and resiliently yielding draw-bar apparatus operatively 25 mounted in a one piece, integrally moulded casting, and secured to the opposite ends of cars, said axle supporting casting being provided with journal boxes fitting the axles of said trucks, and having packing box members at their outer ends, said draw-bar apparatus comprising a housing box portion, a compressive spring in said housing box, a draw-bar extending through said housing 30 box and spring, and means mounted on said draw-bar for compressing said spring a predetermined part of its coil closing movement, and means whereby said draw-bar engages said casting's housing box when said 35 spring is at the end of its adjusted compressive movement, said spring compression limiting means comprising a sleeve slidably mounted in said housing box and mounted on the inner end portion of said draw-bar, and a collar on one end of said spring in said 40 housing box and in engagement with the inner end of said spring, an abutment collar on said sleeve outside of said housing box and an abutment on said draw-bar in engagement with said abutment collar, said 45 abutment collar and its sleeve being adapted to be moved to compress said compression spring when said draw-bar is pulled to start said car, and its abutment collar being arranged to engage said housing box after said 50 car is started, without compressing the coils of said spring to such extent that they bear against each other.

11. In a device of the character described, the combination with a casting adapted to 60 be bolted to a car frame, and having axle bearings on its opposite end portions, and a central transversely arranged housing, of a draw-bar which extends through said housing and beyond the ends thereof, having 65 an eye on one end, a collar on said draw-

bar which abuts against one end of said housing, a compression coil spring surrounding said draw-bar and interposed between said collar and the opposite end of the housing, a sleeve on said draw-bar abutting at one end against said collar and extending through and beyond the adjacent end of the housing, a second collar on the draw-bar, and means for rigidly holding the same against the outer end of said sleeve, 75 whereby, when the eyed end of the draw-bar is forcibly drawn upon, the spring is first compressed by the first mentioned collar until the second mentioned collar engages the end of the housing when the force of the 80 pull is transferred from the spring to the housing.

12. In a device of the character described, the combination with a car frame; of truck castings secured to said frame in pairs; having axle bearings and central transversely arranged housings; draw-bars in said housings which extend through and beyond the ends of said housings, thereby to connect with other cars, a sleeve on each draw-bar 90 which extends through one end of the housing, a collar on each draw-bar in the housing and abutting against the adjacent end of the housing and of the sleeve, a second collar on the draw-bar and means for holding it against 95 the outer end of the sleeve, expansion coil springs in the housings which surround the draw-bars and are interposed between each of the first mentioned collars and the opposite end of the housing, the sleeves being 100 on the opposing ends of the draw-bars, whereby, when either draw-bar is forcibly drawn upon, its spring is compressed by the first collar until the second collar engages the housing, when the second spring is compressed until its second collar engages the housing; when the pull is then transferred to the next car, the springs of each car being compressed before the drawing power is 105 transferred to the next succeeding car, and means for preventing axial rotation of the draw-bars.

13. In a device of the character described, the combination with a car frame, of a truck casting secured to said frame, having axle 115 bearings on each end which terminate in cylindrical boxings, and a transverse housing midway of the length of said casting, an axle extending through and beyond said bearings, wheels on the axle ends having 120 hollow hubs which enter said boxings, rollers interposed between the axles and the inner faces of the hubs, and means including a pin and a washer, for securing said wheels to said axles, draw-bars in said housings 125 having stops and springs for first receiving the pull on said draw-bars before the stops engage the housings.

14. In a device of the character described, the combination with axle supporting cast- 130

- ings having open topped transverse housings centrally of their length; of draw-bars extending through and beyond said housings, having stops on their opposing ends outside the housings, stops on said draw-bars within the housings, and compression coil springs surrounding said draw-bars and interposed between the latter stops and the opposite ends of the housings, whereby, when a forcible pull is exerted upon either draw-bar, its spring receives the force of the pull before the outer stop engages the housing, when the pull is transferred to the other spring, which receives the same before its outer stop engages the housing. 15
- 5 the housings, stops on said draw-bars within the housings, and compression coil springs surrounding said draw-bars and interposed between the latter stops and the opposite ends of the housings, whereby, when a
- 10 forcible pull is exerted upon either draw-bar, its spring receives the force of the pull before the outer stop engages the housing, when the pull is transferred to the other spring, which receives the same before its outer stop engages the housing.

In testimony whereof I affix my signature in presence of two witnesses.

CHARLES S. CARD.
